UNITED STATES PATENT OFFICE

156,724

BEVERAGE HEATING APPLIANCE

Gilbert C. Gettelman, Hartford, Wis.

Application October 27, 1948, Serial No. 149,322

Term of patent 14 years

(Cl. D81—10)

To all whom it may concern:

Be it known that I, Gilbert C. Gettelman, a citizen of the United States, residing at Hartford, in the county of Washington and State of Wisconsin, have invented a new, original, and ornamental Design for a Beverage Heating Appliance, of which the following is a specification, reference being had to the accompanying drawing, forming part thereof.

In the drawing:

Fig. 1 is a perspective view of a beverage heating appliance looking principally from the front and one side, showing my new design; and

Fig. 2 is a perspective view thereof looking principally from the rear and one of the sides.

The opposite side of the beverage heating appliance is substantially like the side illustrated in Fig. 2.

The dominant features of my design are shown in full lines.

I claim:

The ornamental design for a beverage heating appliance, substantially as shown and described.

GILBERT C. GETTELMAN.
